Patented May 3, 1910.

2 SHEETS—SHEET 2.

UNITED STATES PATENT OFFICE.

WILLIAM F. CREMEAN, OF LOGAN, OHIO.

SUPPORTING-SADDLE FOR RUNNING-BOARDS.

956,945.

Specification of Letters Patent.

Patented May 3, 1910.

Application filed January 15, 1910. Serial No. 538,181.

To all whom it may concern:

Be it known that I, WILLIAM F. CREMEAN, a citizen of the United States, residing at Logan, in the county of Hocking and State 5 of Ohio, have invented certain new and useful Improvements in Supporting-Saddles for Running-Boards, of which the following is a specification.

My invention relates more particularly to 10 run board saddles employed for securing the running boards to car roofs.

The objects of my invention are to do away with the nailing or bolting of run boards on wooden saddles thereby avoiding 15 decay and needless repairs, and at the same time effecting a construction which is readily and firmly placed in position with a minimum cost as to the material used, time and expert labor employed in its instalment.

20 The invention consists in features of structural advantages, and relative arrangements of the parts, which will be hereinafter more fully described and particularly pointed out in the appended claims.

25 In the two sheets of drawings, similar characters indicate the same parts throughout the several figures.

Figure 1 is a transverse section of part of a car roof showing one of the run board 30 saddles in position, Fig. 2 is a perspective view of the saddle shown in Fig. 1, removed from the car roof, Fig. 3 is an end view of this saddle, Fig. 4 is a sectional view taken on line IV—IV of Fig. 1, Figs. 5, 6 and 35 7 are respectively elevation, plan, and end views of a modified form of my invention, and Fig. 8 is a sectional view taken on line VIII—VIII of Fig. 5.

Referring to Fig. 1, 1 represents the board 40 or metal covering of an ordinary freight-car, which may be supported upon the usual purlins and earlines, and forms no essential part of my invention and hence will not be more fully described or shown. Attached 45 to the roof 1 at suitable distances apart is one of my improved forms of run board saddle 2, which consists of a truss or frame preferably of the form shown, and which may be made of malleable iron, cast iron or 50 steel, pressed steel or any other suitable material. Each of said saddles is firmly secured to the roof of the car by means of a central bolt 3, passing through an opening 4, in the center of the saddle, and also the 55 ridge timber or purlin 5 of the car roof, and if further security is desired, a screw 6 may

be passed through the hole 7, in each end flange, as shown in Figs. 1 and 2.

The roof saddle 2, as will be seen by reference to Figs. 1 and 2 consists primarily of a 60 base 8 having the angle of its under side so formed as to conform to the pitch of the car roof. Supported on said base 8 by any suitable form of web or legs integrally formed therewith, is an upper horizontal section 9, 65 on which the run boards 10, 10, are supported and held as hereinafter to be described. At suitable distances on the upper side of section 9 are provided lugs 11, 11, which may be of any cross-section or tapered, 70 and provided with an opening 12, and while I have shown two, I do not care to limit myself to their number or distribution as this will depend on the width of run boards used. 13, 13, are retaining caps or clips 75 adapted to fit over said lugs 11, 11, and which are provided with an overhanging head, and a hole 14, corresponding to the opening 12, so that the lug and cap may be securely fastened together by any suitable 80 key or cotter pin 15, for purposes to be presently described.

16, 16, are extensions at the ends of the horizontal section 9, and are provided with inwardly projecting heads which are adapted 85 to engage the upper outer edge of the outer run boards as shown and while I have so illustrated my invention and prefer to so construct the same, the essential features of my invention could be practiced without 90 their extensions, as will be readily seen by one skilled in the art of car building.

17, 17, are either round, square, or pointed small lugs projecting from the upper side 95 of section 9, and may be multiplied or so disposed in any manner for engaging the undersides of the run boards, (see Figs. 1 and 2), and prevent them from creeping or being displaced in the direction of the length of the car, and to further secure against such 100 movement of the run boards, I may provide the caps 13, and extensions 16, with run board engaging webs 18, 18.

In order to make the saddle more substantial and firm, I have increased the bearing 105 surface of the same by a central circular enlargement 20, which may be omitted if so desired.

The construction and operation of the two modified forms of my invention are substantially the same and the form illustrated 110 in Figs. 1 to 4, was more particularly de-

vised for use in connection with cars having wooden roofs, while that shown in Figs. 5 to 8, being adapted for metal roof cars.

In assembling the parts of my invention 5 and properly applying the same to a car roof, one securely fastens at correctly spaced intervals, a saddle 2 as above described and shown in Fig. 1. The run boards 10, 10, are then properly placed on the horizontal section 9, and fitted between the lugs 11, 11, and extensions 16. If small lugs 17, or webs 18, are employed said run boards 10, must be correspondingly cut out and snugly fitted thereto. After the run boards 10, are suitably placed and fitted as above indicated, the caps 13, are slipped down over the lugs 11, until the top of each cap is flush with the run boards, and locked to the lugs by means of the pins 15, inserted in the registering holes 12, and 14. Thus it will be seen by this one operation, the enlarged or expanded head of caps 13, will engage the upper side of the run boards 10, and firmly and quickly secure them in position,—and a mere reversal of these operations enable one to quickly remove any one of the run boards for repairs.

From the foregoing description of my invention and method of applying the same, 30 it will be seen, that I have produced a run board saddle for cars which is entirely of metal, having no parts subject to decay, or nails to work out, thereby causing the run boards to become loose and get out of place, 35 and said boards can be put in place and firmly secured with only a saw and hatchet, thereby materially reducing the cost and maintenance of run boards on cars. Furthermore the roofing boards of a car can be 40 renewed without being required to remove the run boards from their saddles, and all that is necessary is to unfasten the saddles, and move aside the saddles with attached run boards. Also any one of the several run 45 boards can be repaired without disturbing any of the others and are openly supported above the plane of the roof of the car, thereby permitting the sun and air to reach every part, to quickly dry the same 50 and prevent decay.

Having now fully described my invention, what I claim as new and desire to secure by Letters Patent is:

1. A saddle for running boards for car 55 roofs comprising a horizontal section adapted to support running boards, means for fastening said section to a car roof, lugs on the upper side of said horizontal section and disposed between the running boards, and 60 retaining caps adapted to engage said lugs and edges of the boards, to hold said running boards on the horizontal section.

2. A saddle for running boards for car 65 roofs comprising a horizontal section adapted

to support running boards, means for 65 fastening said section to a car roof, lugs on the upper side of said horizontal section and disposed between the running boards, retaining caps adapted to engage said lugs and edges of the boards, to hold the running boards on the horizontal section, and means engaging the running boards for preventing their displacement in the direction of their length.

3. A saddle for running boards for car 75 roofs comprising a base adapted to fit over the center and inclined sides of a car roof, a horizontal section made integral with said base and adapted to receive and support running boards, means for securing the base 80 to a car roof, and means between the running boards adapted to be detachably connected to the horizontal section and firmly clamp the running boards at their edges to the saddle.

4. A saddle for running boards for car roofs comprising a horizontal section adapted to support running boards, means for fastening said section to a car roof, lugs on the upper side of said horizontal section 90 provided with openings, retaining caps provided with openings registering with said lug openings and adapted to be seated over said lugs and hold the running boards on the horizontal section, and pins passing 95 through the openings of said lugs and caps.

5. A saddle for running boards for car roofs comprising a horizontal section adapted to support running boards, means for fastening said section to a car roof, integral 100 lugs on the upper side of said horizontal section and between the running boards, retaining caps adapted to removably engage said lugs and edges of the running boards, to hold the running boards on the horizontal 105 section, and means engaging the running boards for preventing their displacement in the direction of their length.

6. A metallic saddle for running boards for car roofs comprising a base adapted to 110 fit over the center and inclined sides of a car roof, a horizontal section made integral by a web with said base and adapted to receive and support running boards, lugs on upper side of said horizontal section and 115 between the running boards, means for securing the base to a car roof, and removable caps or retaining devices adapted to be detachably connected to the lugs of the horizontal section and firmly clamp the running 120 boards at their edges to the saddle.

In testimony whereof, I affix my signature in presence of two witnesses.

WILLIAM F. CREMEAN.
